UNITED STATES PATENT OFFICE

161,645

DISPENSING CONTAINER FOR LIQUIDS

Leo D. Reimann, Salem, Oreg.

Application July 18, 1949, Serial No. 3,978

Term of patent 14 years

(Cl. D58—8)

To all whom it may concern:

Be it hereby known that I, Leo D. Reimann, a citizen of the United States, residing at Salem, in the county of Marion and State of Oregon, have invented a new, original, and ornamental Design for a Dispensing Container for Liquids, of which the following is a specification, reference being had to the accompanying drawing, forming a part thereof.

Fig. 1 is a side elevational view of a dispensing container for liquids, showing my new design.

Fig. 2 is a top plan view.

Fig. 3 is a side perspective view.

Fig. 4 is another side perspective view thereof.

I claim:

The ornamental design for a dispensing container for liquids, as shown.

LEO D. REIMANN.
